HINGE LEAF

Joseph Yaskulka, Alliance, Ohio, assignor to Lake Park
Tool and Die, Inc., Youngstown, Ohio, a corporation
of Ohio

Filed May 6, 1965, Ser. No. 85,143

Term of patent 14 years

(Cl. D10—9)

FIG. 1

FIG. 2

FIG. 4

FIG. 3

FIG. 5

FIG. 1 is a perspective view of a leaf hinge, portions of the insert pattern being omitted for ease of illustration;

FIG. 2 is a top plan view of the device of FIG. 1;

FIG. 3 is a side elevational view of the device of FIG. 1;

FIG. 4 is a cross sectional view along the line 4—4 of FIG. 1;

FIG. 5 is a rear elevational view of the device of FIG. 1.

The dominant features of the design reside in the portions shown in full lines.

I claim:

The ornamental design for a hinge leaf, as shown and described.
